UNITED STATES PATENT OFFICE.

JOSEPH A. GOETHE, OF HOUSTON, TEXAS, ASSIGNOR OF ONE-HALF TO G. W. SANSOM,
OF HARRIS COUNTY, TEXAS.

HOOD ATTACHMENT.

Application filed December 15, 1925. Serial No. 75,545.

This invention relates to new and useful improvements in a hood attachment.

One object of the invention is to produce an attachment for a motor vehicle hood 5 designed to prevent the leakage of water through the hood onto the wiring and spark plugs of the vehicle motor beneath.

With the above and other objects in view this invention has particular relation to 10 certain novel features of construction and arrangement of parts an example of which is given in this specification and illustrated in the accompanying drawings, wherein:—

Figure 1 shows a plan view of a motor 15 vehicle hood showing the attachment applied thereto and partly broken away.

Figure 2 shows a cross sectional view thereof on the line 2—2 of Figure 1, and

Figure 3 shows an enlarged cross sectional 20 view of the attachment.

Referring now more particularly to the drawings, wherein like numerals of reference designate similar parts in each of the figures the numeral 1 designates the hood as 25 a whole. This hood is jointed longitudinally along the top, in the usual way, forming the hinge joint 2. This joint, in some

makes of motor vehicles, is not water tight and in case of rain the water is permitted to leak through the joint onto the motor 30 wiring and spark plugs causing a short circuit of the electric current.

In order to avoid this leakage the attachment herein described, has been provided. This attachment comprises a long guard 35 strip, 3, concavo-convex in cross sectional contour and arranged lengthwise of and above the joint 2, so as to lie over said joint and with its convex side upwardly. At one edge this guard strip has a plurality of 40 spaced lugs 4, hinged thereto, turned inwardly and riveted or otherwise secured to the hood 1. These lugs hold the guard strip in place without interfering with the flexibility of the hood along its joint 2. 45

What I claim is:—

The combination with a motor vehicle hood having a lengthwise joint, of a guard strip hinged at one edge to the hood and disposed lengthwise of and over said joint. 50

In testimony whereof I have signed my name.

JOSEPH A. GOETHE.
